UNITED STATES PATENT OFFICE.

WILLIAM T. BAILEY, OF NASHVILLE, TENNESSEE.

FIREPLACE BASKET.

Application filed January 29, 1927. Serial No. 184,616.

This invention relates to fireplace baskets and primarily it is an object of the invention to provide a device of this kind with means whereby it may be readily mounted 5 within a fireplace frame irrespective of the relative spacing or varying lengths or thicknesses of the frame lugs generally employed.

Another object of the invention is to provide a basket at each side portion with a 10 structure providing a slot having its lower extremity provided with an open portion to facilitate the requisite application or removal of the basket with respect to the fireplace frame lugs.

15 The invention consists in the details of construction and in the combination and arrangement of the several parts of my improved fireplace basket whereby certain important advantages are attained and the device rendered simpler, less expensive and otherwise more convenient and advantageous for use, as will be hereinafter more fully set forth.

20 The novel features of my invention will hereinafter be definitely claimed.

In order that my invention may be the better understood, I will now proceed to describe the same with reference to the accompanying drawing, wherein:

25 Figure 1 is a view in rear elevation of a fireplace basket constructed in accordance with an embodiment of my invention;

Figure 2 is a view in side elevation of the structure as illustrated in Figure 1;

30 Figure 3 is a fragmentary sectional view taken substantially on the line 3—3 of Figure 2.

35 As disclosed in the accompanying drawing, B denotes a fireplace basket of a conventional design and of desired dimensions, said basket including vertically disposed end bars or members 1.

40 The upper portion of each of the end bars or members 1 is provided with an inwardly 45 or rearwardly disposed lug 2 of requisite dimensions and which has its outer or free end portion continued by a downwardly directed and substantially perpendicularly related elongated arm 3, said arm 3 terminating, as herein disclosed, at a point closely adjacent to the lower extremity of the end bar or member 1.

45 The arm 3 is also substantially in parallelism with the associated end bar or member 1 and disposed, preferably, directly therebehind. The arm 3 is spaced from the

end bar or member 1 in accordance with the size or character of the lug 2 whereby is provided a slot 4.

50 As disclosed in the accompanying drawing, the lower portion of the arm 3 is provided with a laterally and downwardly disposed offset extension arm 5 directed inwardly with respect to the width of the basket B proper. The lower extremity of the 55 extension arm 5 is continued by the lug 6 connected with the adjacent end portion of the basket B and more particularly one of the fingers or bottom bars 7 of the basket proper. This bottom structure carried by 60 the arm 3 results in said arm 3 being maintained in working position with a maximum of strength.

65 It is to be particularly noted that each of the arms 3 and the parts concomitant thereto provide a slot 4 in which may be readily received the fireplace frame lugs 8 with the lug 2 of the basket directly engaging from above the upper frame lug 8 and with the lower lug 8 properly received within the slot 80

4 to effectively hold the basket B properly set. It is also to be understood that the extension arm 5 is offset a distance sufficient with respect to the arm 3 proper to prevent the lug 6 of the extension arm 5 offering any 85 hindrance or obstruction to the desired application or removal of the basket B. In other words, it is to be stated that the lug 6 is spaced inwardly from the outer edge of the vertical bar or member 1 a distance 90 greater than that of the extent the lugs 8 lap the adjacent end portion of the basket.

95 As is clearly illustrated in Figure 1 it is to be noted that the substantially horizontal bottom portion of the basket terminates inwardly of the ends of the front portion and that the rearwardly disposed lugs 2 hereinbefore referred to are carried by those upper portions of the front which extend beyond the ends of the bottom portion and that the 100 lugs 6 carried by the extension arms 5 are secured to the basket at points inwardly of the arms 1. This arrangement results in the lower portions of the slots 4 being open and permitting the frame lugs 8 to readily enter within these slots 4 without interference by the bottom portion upon substantially direct downward movement of the basket.

105 It is also to be understood that each of the 110 arms 3 is of such a length to readily compensate for varying spacing of the lugs 8

at each side of the fireplace frame so that my improved basket may be employed with equal advantage in connection with the various styles of fireplace frames having different spacings of the lugs.

From the foregoing description it is thought to be obvious that a fireplace basket constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

A fireplace basket comprising a body having an upstanding front portion and a substantially horizontal bottom portion, the bottom portion terminating inwardly of the

ends of the front portion, rearwardly disposed lugs carried by those upper portions of the front portion which extend beyond the ends of the bottom portion, arms depending from said lugs and spaced from the adjacent extended extremities of the front portion to provide slots adapted to readily receive the conventional fireplace frame lugs, the lower portions of the arms being continued by extension arms disposed inwardly of the front portion and terminating in lugs attached to the basket at points inwardly of the first named arms thus leaving open the lower ends of the slots provided between said first named arms and the adjacent extremities of the front portion of the basket, said open slots permitting the frame lugs to readily enter within the slots without interference by the bottom portion upon substantially direct downward movement of the basket.

In testimony whereof I hereunto affix my signature.

WILLIAM T. BAILEY.
